Salvatore Russo
Gottlieb H. Blachef
ATTORNEY

UNITED STATES PATENT OFFICE.

SALVATORE RUSSO, OF NEW YORK, N. Y.

ADVERTISING DEVICE FOR CASH REGISTERS.

Application filed May 12, 1927. Serial No. 190,702

This invention relates to a new and useful improvement in cash registers, particularly adapted to display advertising signs, electrically illuminated when change or cash is removed from the special cash holder adjacent the cash register.

The object of the invention is to provide advertising signs of novel construction and arrangement of parts, hereinafter more fully described, claimed, and illustrated in the accompanying drawing.

Fig. 1 is a front elevational view of a cash register embodying my improved advertising signs.

Fig. 2 is a rear elevational view thereof.

Fig. 3 is a vertical transverse sectional view thereof.

Fig. 4 is a fragmentary sectional view taken on the line 4—4 of Fig. 3.

Fig. 5 is a fragmentary sectional view taken on the line 5—5 of Fig. 3.

Fig. 6 is a fragmentary vertical sectional view taken on the line 6—6 of Fig. 3.

Fig. 7 is a top plan view thereof.

In order to fully explain and describe my invention, I have illustrated in the accompanying drawing a cash register such as commonly employed by merchants when making change, or depositing cash received from a customer in payment for goods received or services rendered. The above mentioned cash register comprises the usual container 10, adapted to enclose or cover the mechanism used to operate the cash register and the cash drawer 11, slidably mounted therein. The cash register is also provided with a plurality of extended knobs 12, or buttons, which when depressed, or forced downwardly by the operator or merchant, cause the amount of

the purchase made to appear on the markers 13 which are raised to view intermediate the transparent members 14 and 15. The cash register is also provided with usual handle 15', which when rotated or turned by the said operator, causes the drawer 11 to slidably open or to be extended, permitting the operator to deposit or remove money from the said drawer, as may be desired.

As here embodied my improved device comprises a lever 16, provided with an enlarged portion, pivotally attached at 17 to the front lower portion of the drawer 11. The lever 16 is provided with segment teeth 18, adapted to mesh with the pinion 19, attached to the shaft 20, rotatively mounted in the brackets 21, secured to the drawer 11. The

bevel pinion 22, is attached to the shaft 20 and meshes with the bevel gear 23 attached to the shaft 24. The shaft 24 is slidably positioned in the tubular member 25, rotatively mounted in the brackets 26, attached to the lower member 27 upon which the drawer 11 is slidably mounted. The pin 28 is secured to the shaft 24 and is extended therefrom, engaging in the elongated longitudinal aperture 29 formed in the tubular member 25 so as to permit the shaft 24, when in any desired extended position, to rotate the tubular member 25. The gear 30 is attached to the tubular member 25, and meshes with teeth formed in the rack bar 31, slidably mounted in the guide member 32 secured to the cash register. The rod 33 is attached to the rack bar 31, and is extended upwardly therefrom, and has attached at its extended extremity, a sign member 34, having affixed thereto printed or otherwise, on both sides thereof any desired advertising matter.

The gear 30 meshes with teeth formed in the rack bar 35, slidably mounted in the guide member 36, secured to the said cash register. The rod 37 is attached to the rack bar 35 and is extended upwardly therefrom. The lever 38 is pivotally attached intermediate as at 39, to the cash register. The lever 38 is pivotally attached as at 40, to the extended extremity of the rod 37 and, as at 41, to the arm 42, pivotally attached as at 43 to the sign member 44', slidably mounted in the guide member 45, secured to the cash register. The sign member 44 has affixed thereto, printed or otherwise on both sides thereof, any desired advertising matter.

The above described construction is such as will permit the lever 16, when forced or pushed against the end of the drawer 11, by a person removing cash from the said drawer, to raise the sign members 34 and 44, behind the transparent members 47 and 49, so as to permit the advertising matter, affixed thereto, to be visible. It is to be understood that the said sign members 34 and 44, will be slowly returned to an invisible or normal position by means of the tension spring 46, secured to the rack bar 31, and to any convenient portion of the cash register. It should be understood that the sign members 34 and 44 may be illuminated by the usual electric light bulbs 51 provided to illuminate the said cash register. Attention is called to the feature that an operator of the register

may place money into, or remove money from the register without necessarily disturbing the lever 16. Thus the cash drawer may be operated without operating the advertising signs. This is of great advantage when the display signs recite, for example some article intended for exclusive feminine use, and a gentleman is at the register receiving change for some other article that he purchased.

In Figs. 6 and 7, I have shown a semi-transparent plate member 52 bearing advertising matter, supported by springs 52^a on a semi-transparent bowl 53 having projecting portions 53^c also bearing advertising matter. The bowl 53 is mounted within a coin receiver bowl 54 of star shaped construction attached to the side of the container 10. Lights 52^b are supported from the plate 52, and other lights 52^d are mounted within the bowl 54. Contacts 52^e are connected with these lights, and operable for lighting the lights by manual depression of the plate member 52. The bowl 53 has pins 53' extending therefrom and slidably engaging in apertures in the bowl 54. The expansion springs 55' are wound around the pins 53' and are positioned intermediate the bowl 53 and the lower portion, or bottom of the coin receiver 54 so as to normally hold the bowl 53 in an upwardly extended position free from the bottom of the coin receiver 54. The rack bar 55 is secured to the bowl 53 and is extended downwardly therefrom, through an aperture formed in the bottom of the coin receiver bowl 54. The rack bar 55 engages with the pinion 56 attached to the shaft 57 rotatively mounted on the side of the container 10 and in the bracket 58, attached to the register 10. The bevel pinion 59 is attached to the shaft 57 and meshes with a similar bevel pinion 60 attached to the said tubular member 75. The above described construction is such as will permit the plate member 52 to be forced downwardly by the hand of the said operator, when removing coins placed on the plate member 52 so as to raise the sign members 34 and 44 so as to permit the advertising matter affixed thereto to be visible and at the same time light

certain lights, such as 52^b. It should be understood that coins placed on the plate member 52 is the cash rendered for the goods received, or the change due from the goods received.

Having thus described my invention what I claim as new and desire to protect by Letters Patent of the United States is as follows:

1. In a device of the class described, the combination with a cash register frame, of a display sign arranged for movement into exposed position on the frame, a cash drawer, a lever mounted on the drawer and arranged for manipulation from the interior thereof, and a means for transmitting movement from the lever to the sign.

2. The combination with a cash register having a drawer, of a lever pivotally attached to the drawer and having segment teeth, a shaft rotatively mounted on the drawer, a pinion attached to the shaft and meshing with the said segment teeth, a bevel pinion attached to the said shaft, a tubular member rotatively mounted in the said cash register and formed with an elongated aperture, a second shaft rotatively mounted on the drawer and slidably engaging in the tubular member, a bevel gear attached to the second shaft and meshing with the said bevel pinion, a pin attached to the second shaft and engaging the said elongated aperture for transmitting rotation from the second shaft in any extended position to the tubular member, and display signs connected with the tubular member for motion upon motion of the tubular member.

3. In a device of the class described, a coin receiver bowl, another bowl member movably mounted therein, a plate member movably mounted in the second bowl, lights arranged in the said bowls, display signs arranged for motion into and out of displaying positions, a means for lighting the said lights upon depression of the plate member, and a means for displaying the said signs upon depression of the second mentioned bowl.

In testimony whereof I have affixed my signature.

SALVATORE RUSSO.
